UNITED STATES PATENT OFFICE.

FREDERICK K. WRIGHT, OF SYRACUSE, NEW YORK, ASSIGNOR TO THE
STEAM GAUGE AND LANTERN COMPANY, OF SAME PLACE.

DESIGN FOR A LANTERN-FRAME.

SPECIFICATION forming part of Design No. 25,574, dated June 2, 1896.

Application filed March 4, 1896. Serial No. 581,859. Term of patent 14 years.

To all whom it may concern:

Be it known that I, FREDERICK K. WRIGHT, a citizen of the United States, residing at Syracuse, in the county of Onondaga and State of New York, have invented and produced a new and original Design for Lantern-Frames, of which the following is a specification, reference being had to the accompanying drawing, showing a part thereof.

10 The accompanying drawing is a perspective view of a lantern-frame embodying my new design.

15 The leading feature of my design consists of a frame having straight outer bars which extend from the top to the bottom of the frame and upwardly-converging lower bars which extend from the bottom of the frame upwardly and inwardly to the lower collar.

20 A represents the lower collar or cylindrical housing, which is designed to hold the oil-pot.

B represents the upwardly-converging lower bars, which extend from the bottom of

the frame upwardly and inwardly to the lower collar.

C represents the straight outer bars, which 25 extend upwardly and inwardly from the bottom of the frame to the top thereof.

D represents horizontal rings connecting the upright outer bars. This frame presents the appearance of an open or skeleton frame 30 having straight upright outer members extending from the top to the bottom of the frame and connected by horizontal rings and inwardly and upwardly converging lower members.

35 . What I claim is--

The design for a lantern-frame as herein shown and described.

Witness my hand this 27th day of February, 1896.

FREDERICK K. WRIGHT.
